UNITED STATES PATENT OFFICE.

EARL HANEY, OF MACOMB, ILLINOIS.

INCUBATOR-HEATING SYSTEM.

Application filed May 6, 1926. Serial No. 107,215.

The present invention relates to incubator heating systems especially the type which uses water as the medium to be circulated in order to maintain a predetermined temperature in the incubator for effecting hatching or incubation.

The principal object of the present invention is to positively circulate the water in the incubator by bringing the water to the boiling point without, in the interim before the boiling point is reached, raising the temperature in the incubator to a degree which would preclude or negative incubation.

Another object of the invention is to provide a water circulating system for incubators which will insure boiling of the water in a minimum period of time but which automatically causes the water to cease boiling as soon as the temperature in the incubator reaches a predetermined degree.

Other objects of the invention will be apparent from the following description of the present preferred form of the invention, wherein:

25 Fig. 1 is a horizontal sectional view of an incubator showing a heating system constructed in accordance with the present invention in top plan associated with the incubator;

30 Fig. 2 is a vertical sectional view of the heater per se;

Fig. 3 is a fragmentary vertical sectional view of an incubator illustrating the application of the present invention thereto;

35 Fig. 4 is a fragmentary elevational view of the water circulating apparatus used in the present invention;

Fig. 5 is a horizontal sectional view of the heater and heat guide; and

40 Fig. 6 is an elevational view of the heat guide per se.

In the drawings, in order to illustrate the application of the present invention an incubator 7 is shown which may be of any standard or conventional design.

The heating system constructed in accordance with the present invention includes a heating body 8 which is adapted to be mounted above a heat element 9, in the present instance shown to be a lamp. The system also embodies a discharge or outlet pipe 10 communicating with the top of the heater and return or inlet pipes 11 communicating with the bottom of the heater. The pipes 10 and 11 communicate with a water manifold consisting of intake and return branches

12 and 13 respectively which are in communication with the pipes 10 and 11 respectively. Upon reference to Fig. 3 of the drawings it will be noted that the pipe 10 60 communicates with a percolating filler cup 14 mounted on top of the incubator which latter communicates with the branch 12 of the water manifold by an auxiliary discharge pipe 10'. The lower ends of the return pipes 65 11 extend through one end of the incubator and lead into the heater 8 at diametrically opposite points. It is to be understood that the number of outlet pipes and return pipes may be increased or diminished if desired. 70

The heater 8 consists of a conically shaped body including outer and inner walls between which a water compartment 15 is provided, the walls being held in spaced relation by studs 16 or other suitable spacing elements. The space between these walls is very narrow so that only a very small volume of water is carried in the heater. The outer wall of the heater is provided near its lower end, and at diametrically opposite 80 points, with nipples 17 which are internally screwthreaded to receive complementary threads on the ends of the return pipes 11. The water may be introduced into the system through a cap 18 detachably mounted 85 on the cup 14 and is permitted to flow through the cup into the branch 12 of the water manifold, thence through the branches 13 and ultimately into the bottom of the heater through the return pipes 11. When 90 the water is heated, in a manner hereinafter set forth, it expands through the pipe 10 and into the cup 14 in an apparent manner.

The heating element is so arranged that the heat generated thereby is directed into 95 the heater body for impingement against the inner wall of said body. In the present instance the element 9 consists of a lamp the chimney of which projects into the heater body so that the heat emanating from 100 the lamp will be carried upwardly through the heater body impinging against the inner wall of the latter so as to heat the water contained in the compartment 15.

In order to control the heat a conventional 105 form of thermostatically operated damper apparatus, generally designated 19, is provided. The damper apparatus may be mounted on top of the incubator, as illustrated in the drawings and includes a pendant damper plate 20 which is arranged to lie above the heater body 8. The damper 110

plate does not come in contact with the heater body due to the interpositioning of the top of an exhaust flue 21. The exhaust flue, in the present instance, is shown to be of conical configuration and is smaller in diameter than the interior diameter of the heater body 8. The flue is equipped with ribs 22 the upper terminals of which are enlarged to provide abutments 23 which rest upon the top of the heater body 8, as illustrated to advantage in Fig. 2 of the drawings. By providing the abutments 23 it will be apparent that the damper plate 20 is prevented from coming in contact with the heater body but may rest upon the top of the exhaust flue. When the damper is elevated above the flue, as shown in Fig. 3, the products of combustion from the heating element 9 are permitted to pass upwardly through the center of the flue. When, however, the damper plate is superimposed on the top of the flue and the abutments, the products of combustion are compelled to pass between the inner wall of the heater body and the outer periphery of the flue 21, ultimately leaving the heater body between the flanges 23.

In use of this device, after water has been placed in the system and the lamp is burning, the heat generated by the lamp will impinge against the inner wall of the heater body to cause boiling of the water in the compartment 15 and this positively effects circulation of the water through the outlet pipe 10, percolating cup 14 and water manifold in the incubator from which latter it flows through the return pipes 11 back into the heater body. This cycle of operation is effected while the damper plate 20 rests upon the top of the exhaust flue. As soon, however, as the desired temperature in the incubator is attained, the damper plate 20 is automatically elevated, in a manner well known in the art, so that the products of combustion are then permitted to pass centrally through the flue 21. It is usually accepted in the art that the heating temperature for proper incubation in the incubator is about 103° F. and in order to produce this temperature it is necessary to heat the water to approximately 150° F. Since the

boiling point of water is approximately 212° F., it is apparent that where the water is heated to only 150° F. that in effect very little, if in fact any, circulation of water is effected. Heretofore, it has not been feasible to heat the water beyond a temperature of 150° F. because by so doing the temperature in the incubator would be correspondingly increased. However, it has been found that in the present invention the water may be heated to the boiling point expeditiously and without unduly increasing the temperature within the incubator. This result is accomplished first due to the narrow water space which is provided in the compartment 15 of the heater body; second, due to an encasement of heat insulation material around the heater body, as indicated at 24; and third, by providing the particular form of exhaust flue herein employed.

It is, of course, to be understood that various changes may be made in this device within the scope of the appended claim since I have herein illustrated and described only a single form of the invention in order to illustrate the principle thereof.

What is claimed is:

In an incubator heating system, a water heater consisting of a conically shaped body including outer and inner walls between which a water compartment is provided, the spacing between said walls being very narrow so that only a very small volume of water is carried in the heater, a heating element extending upwardly into the central passage of the heater from the bottom thereof, an exhaust flue depending into the central passage of the heater from the top thereof and consisting of a conically shaped tubular member having on its exterior a plurality of laterally spaced longitudinal ribs the upper terminals of which are enlarged to provide abutments adapted to rest upon the top of the heater, and a damper superimposed on the top of the said flue and abutments for closing the central passage of the flue, said damper being movable to uncover the said central passage.

In testimony whereof I affix my signature.

EARL HANEY.
